UNITED STATES PATENT OFFICE.

FRANK L. GILMAN, OF LOS ANGELES, CALIFORNIA, ASSIGNOR TO GILMAN SHOCKLESS RAILROAD CROSSING SYNDICATE, OF LOS ANGELES, CALIFORNIA.

RAILWAY-CROSSING.

1,238,063.

Specification of Letters Patent. Patented Aug. 21, 1917.

Application filed October 3, 1916. Serial No. 123,516.

To all whom it may concern:

Be it known that I, FRANK L. GILMAN, a citizen of the United States, residing at Los Angeles, in the county of Los Angeles and 5 State of California, have invented new and useful Improvements in Railway-Crossings, of which the following is a specification.

My invention relates to railway crossings in which the gap in the intersection of two 10 rails is automatically closed or filled up when a train is passing over the crossing; and the objects of my improvements are, to provide a crossing in which the gap or interruption in the rail is automatically filled 15 up without any motor or any similar mechanical operation; to provide a crossing in which the interruption of the rails is always automatically kept filled up ready for a train in either direction, longitudinally as well as cross-wise; to provide 20 a crossing in which a passing train automatically opens a gap in the crossing rails leaving continuous rails in the direction in which the train is passing; to provide a 25 noiseless crossing; the invention consisting in the construction, combination and arrangement of devices hereafter more fully described and claimed, and illustrated in the accompanying drawing, in which—

30 Figure 1 is a top view of my device.

Fig. 2 is a cross section through my device on line 2—2 of Fig. 1.

Fig. 3 is a side elevation in detail of a modified form of the fillers, bearings being 35 provided on the shafts supporting the fillers instead of having the lower ends of the fillers rockingly mounted on the foundation.

Fig. 4 is the top view in detail of another modified form of the fillers, the shafts 40 being extended and crossing one over another.

Fig. 5 is a side elevation in detail of the modified form of fillers shown in Fig. 4.

Fig. 6 is a side elevation in detail of still 45 another form of filler, the filler being provided with an extension end projecting downwardly, two springs engaging with the extension end of the filler between which the extension end of the filler is balanced 50 holding the filler in an upright position.

Fig. 7 is a side view or elevation in detail of still another form of fillers, a coil spring being mounted on the pivot of the filler for holding the filler in an upright position.

Fig. 8 is a side elevation in detail of still 55 another form of fillers, a weight being placed and balanced over the cam on the shaft of the filler between suitable standards.

Fig. 9 is a side elevation in detail of still 60 another modified form of fillers, balancing means being engaged with the lower end of the downwardly extending end of the filler for holding the filler in an upright position.

Similar numbers refer to similar parts 65 throughout the several views.

The fillers 1 are secured to the shafts 2, see Fig. 1. The cams 3 are secured to the shafts 2 at a suitable place between the fillers so as to hold the fillers in an upright 70 position when the flat sides 4 of the cams are placed horizontally, see Fig. 2.

If the rails 5 and 6 are considered as the longitudinal rails, and the rails 7 and 8 as the cross rails, the tops 9 of the fillers close 75 the gaps in the longitudinal rail 5, the tops 10 close the gaps in the longitudinal rail 6, the tops 11 close the gaps in the cross rail 7, and the tops 12 close the gaps in the cross rail 8.

The lower ends 13 of the fillers are rockingly mounted in a recess 14 on the foundation, as shown in Fig. 2. Slight modifications of this support are illustrated in the following figures. In Fig. 3, the shaft 2 is 85 shown as supported in roller bearings 15. In Figs. 4 and 5, the shafts 2 are shown as provided with extension ends 16 crossing one over the other for which a bearing can be constructed as will easily be understood. In 90 Fig. 6 another modified form of the shaft 2 is shown as mounted in the base plate 17 below the rail 18 and the filler 1 is turnably mounted on the shaft with a roller bearing inserted in the filler. In Fig. 7 is still another modified form of the filler 1 shown as being rigidly secured to the shaft 2, which is turnably disposed in a roller bearing 19 below the rail 20.

The wheels 21 of a passing train hit with 100 the flanges of the wheels against the tops of the fillers thereby tipping the fillers over to an inclined position as indicated at 22 in Fig. 2. The cam 3, being also rigidly mounted on the shaft 2 with the filler, tips over at the 105 same time with the filler thereby lifting the bar 23, which is pressed down by a spring 24. As soon as the wheel has passed the top of

the filler the bar 23, being impelled by the spring 24 presses the cam with the flat top side back to a horizontal position thereby bringing the filler back to an upright position. By this operation the gaps in the crossing rails are normally kept closed, and the wheel indicated at 21 in Fig. 2, while pushing the top 12 out of the gap as described above, passes over the top 9, filling 10 the gap in the rail over which the train is passing. The passing of a wheel over the top of a filler as seen in an end view is illustrated at 25, the wheel passing over the top 11.

15 In Figs. 1 and 2, the bar 23 is shown as operating two opposite cams with four fillers, but it will easily be understood that the fillers can be operated singly, and it will also be understood that a weight can be used instead of the spring as illustrated in Fig. 8, the weight 26 being mounted between yokes or guides 27. In Fig. 6, the filler is provided with a downwardly extending end 28, which is balanced between the springs 29 and 30.

20 In Fig. 7, a spring 31 is embedded below the rail 20 surrounding the shaft 2, being connected with one end 32 to the shaft 2 and with the other end 33 to the rail or base plate. In Fig. 9, a spring 34 is engaged with 25 the downwardly extending end 28 holding the filler always in an upright position. Instead of the spring 34, a weight can be used with advantage as will easily be understood.

A weight would always be the same and not failing, which might occur with a spring. 35

Having thus described my invention, I claim:

1. In a railway crossing, a shaft mounted longitudinally below each of the short rails in crossings, fillers secured to the ends of the shafts having tops projecting upwardly into the gaps of the rails flush with the tops of the rails, a flat-faced member secured to the shafts between the fillers, and means mounted adjacent the flat-face members for pressing against the flat faces of the said members adapted to serve as balancing means for the fillers. 40

2. In a railway crossing, a shaft mounted longitudinally below each of the short rails of the crossing, fillers secured to the shafts projecting normally upwardly into the gaps of the rails, means on the shafts forming two projections transversely of the shafts, the projections being on the opposite sides of the shafts in relation to each other on each shaft, and means mounted near the shafts engaging 45 with the projections for automatically holding the fillers in normal upright position yieldingly. 50

In testimony whereof I hereunto affix my signature in the presence of two witnesses.

FRANK L. GILMAN.
